UNITED STATES PATENT OFFICE.

JACOB BUCHLI, OF WINTERTHUR, SWITZERLAND.

HIGH-PRESSURE STEAM BOILER FOR LOCOMOTIVES.

Application filed June 29, 1925. Serial No. 40,299.

To all whom it may concern:

Be it known that I, JACOB BUCHLI, a citizen of the Swiss Republic, residing at Winterthur, Switzerland, have invented an Improvement in High-Pressure Steam Boilers for Locomotives, of which the following description, in connection with the accompanying drawings, is a specification, like characters on the drawings representing like parts.

The present invention relates to high-pressure steam boilers for locomotives.

It is known that with the use of high pressure steam the transformation into mechanical work is the more favorable the higher the pressure in the boiler is. As high pressure steam cannot be used with the ordinary firebox of a locomotive and the known bracing of the shell thereof by stay bolts, other means had to be devised to permit the use of high pressure steam.

The present invention provides for a design of locomotive boilers allowing to use high pressure steam with locomotives. The working of the locomotive stipulates that large quantities of energy must be stored in the boiler and besides the large water space it is essential that the water evaporates quickly. In order to satisfy the latter condition the roof and the side walls of the firebox are formed by water tubes arranged beside each other and flooded by the combustion gases. The particular design and arrangement of these tubes form the subject matter of the present invention.

Constructional examples of the subject matter of the present invention are illustrated on the accompanying drawings, in which—

Fig. 1 is a cross-section through the firebox and the upper boilers or steam drums; Fig. 2 is a longitudinal section along line II—II in Fig. 1 through the firebox and part of one steam drum;

Fig. 3 shows a section along line III—III in Fig. 1;

Fig. 4 shows on a reduced scale a normal water tube element;

Fig. 5 shows on a reduced scale a modified type of a water tube element;

Fig. 6 shows a portion of the upper boilers in a section along line VI—VI in Fig. 1;

Fig. 7 is an elevation of the complete locomotive;

Fig. 8 is a vertical section along line VIII—VIII in Fig. 3;

Fig. 9 shows a modified type of boiler having only one steam drum.

Referring now to the drawings 1 and 1' are the two upper boilers (steam collectors) into which the water tube elements 2 are beaded. As is shown in Figs. 4 or 5, the tube elements consist of the tube 2 of U-shape provided with a short branch 3. The extensions 4 of the tube 2 are of a smaller diameter than the tube 2 (approximately half the diameter) and are bent back and extend outside of and parallel to the shanks of the U-shape. The branch 3 and the free ends of the extensions 4 are parallel to each other so that they can be introduced into corresponding holes of the drums 1, 1' and beaded therein. The insertion of the tube elements into the drums 1, 1' is carried out alternately, i. e. the branches 3 are alternately joined to the drums 1 and 1' whilst the free ends of the extensions 4 are fixed one end in the drum 1 and the other end in the drum 1'. For instance branch 3 of one of the tube elements is connected to the drum 1 and the branch 3 of the adjacent element is connected to the drum 1'. This manner of fixing the tube elements is illustrated in Fig. 6, in which the rows of holes 5 and 5' serve for fixing the free ends of the extensions 4 while for instance the branches 3 of the even tube elements are beaded in the row of holes 6 in the drum 1 and the branches 3 of the uneven tube elements are beaded in the row 7 of holes 7 of the drum 1'. The shanks of the tube elements in the middle portion of the firebox are inclined against the vertical direction and at the ends of the firebox these shanks are vertical as shown at 2' in Figs. 3 and 8.

The extensions 4 of the water-tube elements are protected by the shanks 2 against the radiating heat of the fire, the beading places are protected in the same manner. The lower ends of the tube elements are enclosed in a frame 9 and embedded in an insulating material so that they can freely expand. The drums or steam collectors 1, 1' and tube elements 2 are protected on their outer side with insulating material 10 and are enclosed with sheet iron 11, the insulating material being omitted in Fig. 3. The front wall of the firebox is formed by a wall 12 of refractory material in which the opening 13 for the fire door is provided.

As is shown in Fig. 5 the top part of the

tube element 2 intermediate of the two shanks may be inclined; this permits to arrange the branch 3 near the highest point of that part to prevent a collection of steam bubbles in the tube.

The general arrangement of a high-pressure steam locomotive is illustrated in Fig. 7, which shows in dotted lines the tube elements arranged in the firebox.

10 Instead of two drums or steam collectors only one steam collector may be provided as is illustrated in Fig. 9 in which case the branches 3 and free ends of the extensions 4 of every tube element are beaded to the 15 drum 1".

I claim:

1. In a high-pressure steam boiler for locomotives, a water tube of substantially inverted U-shape for spanning the fire box 20 and having an extension to its shanks bent substantially parallel to and protected by the shanks and a short tubular branch on said tube between the shanks.

2. In a high-pressure steam boiler for locomotives, a water tube of substantially inverted U-shape spanning the fire box and having an extension of each shank of smaller diameter and bent substantially parallel to and protected by its shank, and a tubular 30 branch on said tube between its shanks.

3. A high pressure steam boiler for locomotives comprising in combination two upper boilers, a plurality of water tubes arranged beside each other in the longitudinal direction of the locomotive boiler and forming between them a vaulted fire box, said water tubes consisting of U-shaped tube elements the shanks of which have extensions

of a reduced diameter and bent in the outward and upward direction and substantially parallel to said shanks, and a branch provided on every water tube intermediate of its shanks, said branch and the free ends of said extensions being parallel to each other and one of said free ends being beaded into one of said upper boilers and the other of said free ends being beaded into the other of said upper boilers and said branches being alternately beaded to one or the other of said upper boilers.

4. A high pressure steam boiler for locomotives comprising in combination two upper boilers, a plurality of water tubes arranged beside each other in the longitudinal direction of the locomotive boiler and forming between them a vaulted fire box, said water tubes consisting of U-shaped tube elements with an inclined middle portion, the shanks of which have extensions of a reduced diameter and bent in the outward and upward direction and substantially parallel to said shanks, and a branch provided on every tube intermediate of its shanks and at the highest point of said intermediate portion to prevent an accumulation of steam bubbles, said branch and the free ends of said extensions being parallel to each other and one of said free ends being beaded into one of said upper boilers and the other of said free ends being beaded into the other of said upper boilers and said branches being alternately beaded to one or the other of said upper boilers.

In testimony whereof, I have signed my name to this specification.

JACOB BUCHLI.
